(57) **CLAIM**

The ornamental design for a child monitor having button-hole-attaching transceiver for communication with remote base station, as shown and described.

DESCRIPTION

FIG. 1 is a perspective view of the child monitor having buttonhole-attaching transceiver for communication with remote base station, embodying the design of the present invention shown detached.

FIG. 2 is a front elevational view thereof, the rear elevational view being identical thereto;

FIG. 3 is a right side elevational view thereof, the left side elevational view being identical thereto;

FIG. 4 is a top plan view thereof;

FIG. 5 is a bottom plan view thereof; and,

FIG. 6 is a perspective view of the child monitor having buttonhole-attaching transceiver for communication with remote base station in use; the broken line showing of environmental structure is for illustrative purposes only and forms no part of the claimed design.
